UNITED STATES PATENT OFFICE

HARRY KAHANOWITZ, OF SCRANTON, PENNSYLVANIA

DESIGN FOR A BOTTLE OR SIMILAR ARTICLE OF MANUFACTURE

Application filed August 15, 1929. Serial No. 32,418. Term of patent 14 years.

To all whom it may concern:

Be it known that I, HARRY KAHANOWITZ, a citizen of the United States, residing at Scranton, in the county of Lackawanna and State of Pennsylvania, have invented a new, original, and ornamental Design for Bottles or Similar Articles of Manufacture.

The figure is the face view showing my design of bottle.

I claim:

The ornamental design for a bottle or similar article of manufacture, as shown.

July 25, 1929.

HARRY KAHANOWITZ.
